Patented Apr. 11, 1922.

UNITED STATES PATENT OFFICE.

THORSTEN ZWEIGBERGK, OF LONDON, ENGLAND.

ELECTRIC CONTROLLING SYSTEM.

1,412,589.

Specification of Letters Patent. Patented Apr. 11, 1922.

Application filed March 18, 1920, Serial No. 366,389.

To all whom it may concern:

Be it known that I, THORSTEN ZWEIGBERGK, a citizen of the United States, residing at London, in the county of London, England, have invented a certain new and useful Improvement in Electric Controlling Systems, of which the following is a full, clear, and exact description, reference being had to the accompanying drawings.

10 This invention relates to electric controlling systems wherein a main motor driven controller is actuated through a manually operated master controller. The essential object of the invention is to provide such a system which shall be simple and effective in operation and by which the remote control of a comparatively heavy current may be readily accomplished. Another object is to protect the device by means rendering it impossible to close the circuit through the main motor, once it is broken, except when the main controller is positioned by including all of the resistance. Other specific objects will appear in the following description which relates to the accompanying drawing.

The essential characteristics of this invention are summarized in the appended claims.

The drawing comprises a diagrammatic illustration of a preferred arrangement of this invention and the following description refers to the drawings by suitable characters designating the various elements of the system.

25 The main controller is illustrated as comprising a drum 10 carrying a plurality of main contact plates, 11, 12, 13, 14, 15, and 16 while the broken lines 1, 2, 3, 4, 5, and 6, parallel with the axis of the drum, correspond to the various positions or "notches" of the controller. At 20 is indicated the main positive or plus wire carrying the current, it is desired to regulate, by the main controller 10. This wire leads current to 40 a contact 21, with which a contact 22 is adapted to co-act, and from the contact 22 the current passes through a wire 24 to resistance 25 to which are connected the contacts 31, 32, 33, 34, 35 and 36. From the 45 resistance a wire 26 leads through the main motor 27 and to the ground as indicated at 28. As the contact plates 11 to 16 successively are brought under the contacts 31 to

36 the resistance is cut out by reason of the wires 30 interconnecting the contact plates 55 11 to 16, as shown.

Moving with the main controller, and for convenience shown as mounted on the same drum 10, are auxiliary contacts which co-operate with the manually operated master 60 controller to govern relays in the operation of the system as will be hereinafter more fully described.

The main controller drum is illustrated as rotated by a motor 40 whose armature shaft 45 41 may have a worm 42 co-acting with the worm gear 43 on the shaft of the main controller drum, while current passing through a wire 44, the usual resistance 45 and through the field coils of the motor a wire 70 46 leading to a contact point at 7 to a contact point 8 through the plate 47 to a wire 58 through the armature brushes 57 and the armature, wire 58, wire 48 contact 9 and wire 49 to the ground indicated at 50. A 75 plate or carrier 52 is shown as attached to the pivoted arm 54 carrying a contact 22 and having core or armature 55 within a solenoid coil 56 to actuate the contact 22 as well as move the plate 52 and the contact 80 plate 47 and 9. One of the wires 58 is broken by separated contacts 60 of a relay having a bridge member 62 normally extending across the contacts and carried on a core 63 projecting into a coil 64, while these wires 85 58 may be connected to short circuit the armature by any of the series of contacts 65, 67 and 69, one of each pair being connected with a wire 58 and being adapted to be bridged by contact members 66, 68 and 70 90 carried by solenoid armatures the coils for which are indicated respectively at 71, 72 and 73.

It will be seen that when any of the contact members 66, 68 or 70 are moved to their 95 upper positions, the wires 58 are connected in such a manner as to short circuit the armature. These solenoids for short circuiting the armature are controlled by the master controller indicated at 75, preferably 100 of a drum type, having a plurality of contact plates on its surface and movable to various positions or "notches" as indicated by the vertical broken lines designated 1, 2, 3, 4, 5, and 6. Co-acting with the contact 105 plates on the controller 75 are a series of

contacts 80, 81, 82, 83, 84 and 85 while the contact plates on the controller are interconnected in the usual manner.

The remaining parts of the system shown 5 may be made more clear by referring to them in the course of the following description of the operation of my system.

In position shown in the drawing, the master controller 75 and main controller 10 are in the "off" or inoperative position. If now the master controller is moved to first notch, which on the diagram would be such a movement as to bring the line 1 of the controller 75 under the series of contacts 80

15 to 85, current will pass from a positive or supply wire leading to the contact 80 through the contacts on the controller to the contact 81 thence through a wire 87 solenoid 56 to a contact 88 through a wire 89 to a

20 contact 90 engaging one of the contact plates 91 associated with the main controller drum and thence through a contact 92 to the ground, indicated at 93. The result is, the core 55 is moved upwardly closing the main

25 contacts 21 and 22 so that the main current may pass through the wires 20, 24 and main resistances 25, motor 27 and to the ground. This same movement of the core of the sole-

30 noid 56 carries plate 52 with it, moving the contact plate 47 into engagement with contacts 9 and 7, and grounding wire 146 through contact 8 and plate 86; whereupon

35 current flows through the motor 40. This current cannot cause the rotation of the motor 40 and consequent movement of the drum 10, however, because the armature of the

40 motor 40 is short circuited, at the contacts 65, by current from contact 80 to the contact 83 and wire 94 leading through the relay 71,

45 wire 95 and contact 96, which is bridged across to the plate 91, shown as grounded when the main controller is in this position as previously stated. Thus the movement of the master controller to position 1, causes

50 current to pass through the main motor and all of the main resistance in circuit therewith but does not cause a movement of the main controller.

If now the master controller is moved to position 2, (that is, on the diagram bringing the line 2 of the controller 75 under the row of contacts 80 to 85) the circuit through the relay 71 is broken by reason of the contact 83 passing off from the corresponding contact plate on the controller drum 75, thus breaking the short circuit of the armature of the motor 40 and allowing that motor to rotate, moving the main controller drum to its position 2.

55 The movement of the main controller drum when it reaches position 2, is operated by action of the auxiliary contacts moved by the main controller drum and causing the armature of the motor 40 to again be short circuited at that time by bringing the contact

97 under contact 98 of a wire 99 leading from the solenoid coil 72, connected with the contact 84, which is brought into circuit with the supply wire 80, when the master controller 75 is moved to its second position; in other words, movement of the master controller from position 1 to 2 opens the short circuiting of the armature of the control motor 40, allowing it to rotate the main controller drum but at the same time connects a circuit from the wire 80 through the relay 72 which circuit is closed to the ground by wire 99 and contacts 98 and 97, and 91 and 92, when the main controller motor reaches its second position.

60 When the master controller 75 is moved to its third position (in the diagram bringing the line 3 under contacts 80 to 85) the current is still passing through the main contactor solenoid 56. The short circuit from the armature of the motor 40 is again broken, but is closed by bringing the contact plate on the drum 75 under the contact 85 which closes a circuit through the wires 102, 103 and contact 104, when that contact comes onto a contact plate 105, closing a circuit to the ground at 93 from the supply wire 80; thus moving the contact 70 of the solenoid 73 to short circuit the armature 40 and stop the main controller drum in its third position.

65 The subsequent positions, 4, 5 and 6 of the main controller drum, are reached in the same manner as those heretofore described except, for example, to go from position 3

70 to 4 the short circuit of the armature 40 is broken by the action of the solenoid 64 raising the contact 62, when the master controller is moved to its fourth position bringing a contact plate into engagement with the contact 82, allowing current to flow from the feed wire 80 through the contact 82, wire 110 and coil 64 to the ground at 112. The control motor is stopped when the main controller 10 reaches its fourth position by reason of the contact 83 coming onto another contact plate in the fourth position of the master controller, which passes current through the solenoid relay 71, wire 95 and a contact 96 grounded at 93 as before. At 75 this same time contacts 115 connected by wires 116 with the contacts 60 complete the short circuiting of the armature through connected contact plates 118. These extend across the 4th, 5th and 6th positions of the main controller. The 5th and 6th positions accordingly are reached by the same action of the relays and auxiliary contacts as those to reach the 2nd and 3rd positions of the main controller, there being contacts 98 and 105 connecting with the contacts 98 and 104 to ground the current through the relays 72 and 73 as before. 80 To return the main controller to neutral or "off" position, the master controller 75

is brought to its "off" position, which is that shown in the drawings. This breaks the circuit from the feed wire 80 through the main contact solenoid allowing contact 22, arm 54 5 and carrier plate 52 to drop returning the parts to the position appearing in the drawings.

This brings the parts, under the control solenoid 56, to positions shown, where the 10 current passing through the motor 40 is returned through the wire 46 to the wire 58 through the armature and wires 58 and 48, and contact 9, wire 49 and ground 50, thus changing the direction of the flow 15 through the armature with relation to the field and reversing the motor. This reversing movement must be completed as the solenoid 56 cannot again be actuated until the contact 90 comes onto the offset portion of 20 the contact plate 91, on the main controller drum, which is the neutral position of the main controller; that is, because the plate 86 is separated from the contact 88 the solenoid current cannot be grounded either at 50 25 or 93 until the contact 90 is grounded, whereas when the contact 22 is raised carrying the plate 52 upwardly, the contact plate 86 comes under the contact 88 and serves to ground the solenoid 56 regardless of the position of the 30 auxiliary contacts of the main controller, and as long as the contact 22 is up in engagement with the contact 21. Also when this plate 52 is raised the current passing through the motor 40 and its armature has a path 35 such that the motor rotates in the direction to advance the controller drum 10 from position 1 to position 2, 3, etc.

From this it will be seen that the arrangement of auxiliary contacts is such that the 40 system is in effect, interlocked in a manner making it impossible for the main contactor solenoid to act, once it is broken, until the main controller has reached its off position. This has a material advantage, in that it 45 eliminates blow-outs of fuses and similar difficulties.

Having thus described my invention, what I claim is:

1. The combination with a motor of a series of resistances in circuit therewith, a controller for successively varying said resistances, a motor for actuating the controller, a plurality of means for short circuiting said motor to stop it, and means moved by the 55 main controller for controlling said motor stopping means, said means being selectively operable.

2. The combination with a motor, of a series of resistances in circuit therewith, a controller for successively varying said resistances, a motor for actuating the controller, means for short-circuiting said motor to stop it, said means including a plurality 60

of contacts moved by the controller and adapted to be selectively brought into action. 65

3. In combination, a motor having a plurality of resistances and a circuit controller in series therewith, a motor for actuating the circuit controller, a series of relays for stopping and starting said last named motor, 70 a master controller for operating said relays and auxiliary contacts moved with the main controller for actuating said relays to stop the main controller in its successive positions.

4. In a system of the class described, the 75 combination of a motor in an open main circuit, a variable resistance, means for closing said circuit, a controller adapted to successively vary said resistance, a motor for actuating said controller, a master controller, 80 a series of auxiliary contacts moved by the main controller and connected together, and circuit making and breaking means for governing said auxiliary motor under control of said master controller and said auxiliary contacts. 85

5. The combination of a main motor, a resistance in series therewith, a main controller for governing said resistance, an auxiliary motor for operating the main controller, a master controller for governing the main motor circuit and auxiliary motor circuit, a series of contacts moved with the main controller, and circuit making and breaking devices adapted to control the stopping and starting of the auxiliary motor at each successive position of the main controller and connections whereby the master controller closes a circuit to said main motor directly in the initial position of said main 100 controller. 90

6. The combination with a main motor and resistances in circuit therewith of a main controller movable to successive positions to vary said resistance, an auxiliary 105 motor for moving the main controller, a master controller for governing said main motor circuit and said auxiliary motor, circuit making and breaking means for short circuiting the armature of said auxiliary 110 motor consequent upon the main controller reaching each successive position.

7. In combination, a motor and resistances in circuit therewith, a main controller for cutting out said resistances in a series 115 of successive positions, an auxiliary motor for actuating said main controller, a circuit therefor, a master controller governing said circuit and the circuit of the main motor, means whereby first and each successive position of the master controller may close the circuit through the main motor, a series of auxiliary contacts movable with the main controller, relays governed by the master controller and said contacts for successively controlling the circuit of the auxili- 120 125

- ary motor to stop it in each successive position of the main controller, and means for reversing said auxiliary motor consequent upon breaking of the circuit through the 5 main motor.
8. In combination, a motor and resistances in circuit therewith, a main controller for cutting out said resistances by movement to a series of successive positions, an auxiliary 10 motor for actuating said main controller, a circuit therefor, a master controller governing said circuit and the circuit of the main motor, a series of auxiliary contacts movable with the main controller and relays 15 governed by the master controller and said contacts for successively controlling the circuit of the auxiliary motor to stop it in each successive position of the main controller, means for reversing said auxiliary 20 motor consequent upon breaking of the circuit through the main motor, and means for closing the circuit through the main motor only when the main controller is positioned to include said resistances.
- 25 9. In combination a motor having a plurality of resistances in circuit therewith, a circuit controller for said motor, an auxiliary motor for actuating the circuit controller, a master controller, relay devices 30 governed thereby to short circuit the auxiliary motor, separate means for opening the circuit through the auxiliary motor, and means for remaking or closing said circuit consequent upon movement of the main 35 controller.
10. In combination, a motor and resistances in circuit therewith, a main controller for said motor adapted to cut out said resistances, an auxiliary motor for actuating the main controller, relays for short 40 circuiting the armature of said auxiliary motor to stop the motor consequent upon the main controller reaching each successive position, means for opening said short circuit independently of said relays, and means 45 moved by the main controller for remaking said circuit whereby each relay may function for another position of the main controller.
- 50 11. In combination, a motor having a plurality of resistances in circuit therewith, a motor for actuating the controller, a plurality of short circuiting devices for said actuating motor, contacts moved with said 55 controller to open the short circuiting devices, and a master controller for actuating said devices.
12. The combination with a motor, a series of resistances in circuit therewith, a 60 controller for successively varying said resistances, a motor for actuating the controller, means for short circuiting said second motor to stop it, and a plurality of means moved by the main controller for con- 65 trolling said motor stopping means, and connections allowing the closing of the circuit through the main motor only when the main controller is in its off position.
13. The elements described in claim 3 in combination with a contact for closing said 70 main circuit and a switch carried thereby in co-operation with the contact on said main controller whereby the circuit through the main motor can be closed only when the main controller is in a certain position. 75
14. A system of the class described in claim 4 wherein the means for closing the main circuit may be active only in a certain position of the main controller and which may remain active through successive 80 positions of the main controller.
15. In a system of the class described, the combination of a motor in an open main circuit, means for closing said circuit, a variable resistance, a controller adapted to successively vary said resistance, a motor for actuating said controller, a master controller, a series of auxiliary contacts moved by the main controller, and circuit making and breaking devices for governing 85 said auxiliary motor under control of said master controller and said auxiliary contacts, and means actuated by the main circuit closing means to reverse the motor under control of contacts carried by the main 90 controller. 95
16. The combination with a main motor and resistances in circuit therewith, of a main controller movable to positions to vary said resistances, an auxiliary motor for moving said main controller, a master controller for governing said main motor circuit through said main controller, circuit making and breaking means for controlling the auxiliary circuit to short circuit the auxiliary 100 motor when the main controller reaches a position corresponding to the position of the master controller. 105
17. In combination, a motor having a plurality of resistances in circuit therewith, a main controller governing the resistance in the circuit, a motor for actuating the controller, short circuiting means for said actuating motor, contacts moving with said actuating motor, contacts moving with said controller to operate the short circuiting means and a master controller cooperating with the main controller to govern the actuation of 110 said means. 115
18. The combination of a motor having a plurality of resistances in circuit therewith, a main controller for successively varying such resistances, an auxiliary motor for actuating the main controller, a master controller, a series of selective contacts on each 120 controller, the contacts on each controller being connected together, means for selectively connecting the contacts on the two con- 125

trollers in various positions of the controllers, said means comprising independent conductors, said contacts on the controllers being connected respectively to the 5 power and return wires of a circuit controlling the operation of said auxiliary motor.

19. In an electrical controller system, two controllers each having selective contacts progressively arranged thereon whereby 10 when the first controller is moved to a position in advance of the position occupied by the second controller, said contacts on the two controllers being connected when the second controller occupies a position behind 15 that of the first controller, a wire connected to the contacts on one controller, a return wire connected to the contacts of the other controller, and means for moving the second controller, said means being under control 20 of the circuit closed by the connections between said controllers.

20. In an electrical controller system, two controllers, means for positioning one controller by means of the other controller, said means comprising a plurality of sets of contacts on each controller, the contacts in each set being progressively arranged, corresponding bridging contacts occupying all of the positions of the next succeeding set of contacts on each controller, connecting means 25 for connecting the corresponding contacts on one controller with the corresponding contacts on the other controller when their respective controllers occupy positions corresponding to the contacts respectively, all of 30 said contacts on one controller being connected with one wire of a circuit, and all of the contacts of the other controller being connected with a return wire of said circuit.

In testimony whereof, I hereunto affix my 35 signature.

THORSTEN ZWEIGBERGK.
